UNITED STATES PATENT OFFICE.

RALPH R. GRIFFITH, OF MINNEAPOLIS, MINNESOTA.

WHEEL.

1,268,241.

Specification of Letters Patent.

Patented June 4, 1918.

Application filed May 25, 1916. Serial No. 99,743.

To all whom it may concern:

Be it known that I, RALPH R. GRIFFITH, a citizen of the United States, residing at Minneapolis, in the county of Hennepin 5 and State of Minnesota, have invented certain new and useful Improvements in Wheels, of which the following is a specification.

My invention relates to wheels and has 10 for an object to provide a flanged rim and hub connected by a web member formed out of a single sheet of metal by cutting sets of inwardly-projecting and outwardly-projecting radial arms out of the sheet without 15 waste of material and alternately bending the arms away from the sheet and securing them to the flanges of the hub and rim.

The full objects and advantages of my invention will appear in connection with the 20 detailed description thereof and are particularly pointed out in the claims.

In the drawings, illustrating the application of my invention in one form,—

Figure 1 is a front elevational view of my 25 improved wheel. Fig. 2 is a sectional view taken on line 2—2 of Fig. 1. Fig. 3 is a front view partly in section of a modification.

In the construction of my improved wheel 30 I employ a rim 10 provided with flanges 11 and 21, which rim may be rolled out of sheet metal and welded together in the usual manner. A hub 12 either cast or otherwise formed, having flanges 13 and 23, is used 35 in conjunction with the rim 10 and is secured to it by a web member now to be described. A sheet of metal is first cut into a circular disk of a diameter somewhat greater than the inner diameter of the rim 40 10 and is then punched at the center to provide a circular hole of a diameter somewhat less than the external diameter of the hub 12. On a circle midway between the outer and inner circumferences of this sheet is 45 punched a number of small holes 14 of which there must be an even number spaced equidistantly. The sheet is then sheared along radial lines to the holes 14, first along lines 15 from the outside of the plate to every other hole, and secondly along lines 50 16 from the inner circumference to the remaining holes. In this manner a number of arms 17, 18, 19 and 20 are formed, of which the arms 17 and 18 project radially 55 outward from the sheet and have diverging

sides, and of which the arms 19 and 20 project radially inward and have converging sides. Of the outwardly-projecting arms each alternate arm 17 is bent away from the sheet in the same direction and is riveted to one of the flanges 11 of the rim 10 and the remaining outwardly-projecting arms 18 are bent in the opposite direction and riveted to the other flange 21 of the rim 10. Similarly, the alternate inwardly-projecting arms 19 and 20 are bent away from the sheet in opposite directions and riveted to the flanges 13 and 23 of the hub 12. In this manner the central member is secured to both flanges of the rim and hub and hence 60 rigidly holds the same in their proper relations.

As illustrated in Fig. 3, my invention is readily applicable to a split pulley in which the hub 12 is split, as indicated at 30 and 31, 65 along one of the radial lines of cleavage of the inner portion of plate. The plate 17 is cut across, as indicated at 32 and 33, from cut-out portions 34 and 35 on said radial lines to cuts 15 which are numbered 36 and 80 37 and which are also in a common radial line. The rim 10 is severed in the line of said last named radial cuts, as indicated at 38, and one end is provided with a lip 39 which extends beneath a flange 40 on the 85 other end. Lugs 41 and 42 on the respective ends are adapted to receive bolts 43 by which the pulley is clamped in position.

The advantages of my invention are manifest. The wheel can be constructed entirely 90 out of sheet steel and will hence be of great strength and can be made with simple tools. Due to the yielding nature of the arms before they are secured, the sheet metal member may be readily placed between the hub 95 and the rim. The wheel is perfectly trussed in all directions on account of the double sets of triangles formed by the arms and will hence tend to remain true.

I claim:

1. A wheel comprising a rim, a hub and a sheet metal member connecting said rim and hub, alternate inner portions of said member being secured to opposite sides of said hub and alternate outer portions of 105 said member being secured to opposite sides of said rim.

2. A wheel comprising a rim, a hub and a sheet metal member connecting said rim and hub, said member having a plurality of in- 110

ner sections bent alternately in opposite directions and secured to said hub and said member also having a plurality of outer sections bent alternately in opposite directions and secured to opposite sides of said rim.

3. A wheel comprising a rim, a hub and a sheet metal member connecting said rim and hub, said member having a plurality of inner sections defined by cuts extending from the hub toward the rim with alternate sections bent in opposite directions and secured to said hub, and said member also having a plurality of outer sections defined by cuts extending from the rim toward the hub with alternate sections bent in opposite directions and secured to opposite sides of said rim.

4. A wheel comprising a flanged rim, a flanged hub, and a central member formed of sheet metal having one set of outwardly-projecting arms cut out of the body of the metal and alternately secured to the flanges of the rim and another set of inwardly-projecting arms cut out of the body of the metal and alternately secured to the flanges of the hub.

5. A wheel comprising a rim, a hub and a sheet metal member connecting said rim and hub, said member having a plurality of arms defined by cuts extending in radial lines from the circumference substantially half way to the inner margin with alternate arms bent in opposite directions and secured to said rim and said member also having a plurality of arms defined by cuts extending in radial lines from the inner margin substantially half way to the circumference in staggered relation to said first named cuts with alternate arms bent in opposite directions and secured to said hub.

6. A wheel comprising a flanged rim, a flanged hub, and a central member formed out of an annular disk of sheet metal by cutting the sheet in a number of radial lines

from the circumference half-way into the disk and without loss of material and alternately bending outward in opposite directions the arms thus formed and securing them to the flanges of the rim and by cutting the sheet in a number of radial lines from the inner margin half-way in to the disk in staggered relation to said first-named cuts without loss of material and alternately bending the arms thus formed outwardly in opposite directions and securing them to the flanges of the hub.

7. A pulley wheel comprising a rim and hub, and having a central member formed of sheet metal with arms cut out of the body of sheet metal and secured to the rim and hub, said hub being split on opposite sides along the radial lines of cleavage for some of said arms, and the rim being split at one side on a radial line of cleavage, and means for securing together the cleft portions of the hub and rim.

8. A pulley wheel comprising a rim and hub and a central member consisting of a disk of sheet metal having arms formed by cutting the sheet in a number of radial lines from both the outer and the inner margin of the disk to points on a circle midway therebetween, said arms being bent alternately in opposite directions along said circle and being secured at their ends to the hub and rim, respectively, said hub being cut on opposite sides along a set of inner radial lines of cleavage, said rim being cut along the adjacent outer radial lines of cleavage, and the disk being cut to join the said outer and inner radial lines of cleavage, and means for securing the pulley sections together.

In testimony whereof I affix my signature in presence of two witnesses.

RALPH R. GRIFFITH.
